UNITED STATES PATENT OFFICE.

DONALD H. FAIRCHILD, OF DENVER, COLORADO.

BALL-MILL.

1,275,184.

Specification of Letters Patent.

Patented Aug. 6, 1918.

Application filed May 31, 1917. Serial No. 171,902.

To all whom it may concern:

Be it known that I, DONALD H. FAIRCHILD, a citizen of the United States, residing at the Princess Apartments, #25, in the city 5 and county of Denver and State of Colorado, have invented certain new and useful Improvements in Ball-Mills; and I do declare the following to be a full, clear, and exact description of the invention, such as will enable 10 others skilled in the art to which it appertains to make and use the same, reference being had to the accompanying drawings, and to the characters of reference marked thereon, which form a part of this specification.

My invention relates to improvements in ball or pebble mills, my object being to provide a construction of this class which shall have several improvements over those in ordinary use, so far as I am aware. My object is to provide a mill of this character in which the product shall be characterized by less slime, and which shall also have a greater capacity than the mills of this type heretofore in vogue. In the accomplishment of this result I make provision for discharging the pulverized product at both ends of the machine. Heretofore, so far as I am aware, the discharge from mills of this type has 20 been at one end only, being the end remote from the feed end. It is well understood that grinding devices of this character are mounted upon end trunnions. In the regular form of the well known construction 25 both of these trunnions are hollow, the material being fed by a screw through one of the hollow trunnions, while the pulverized or granulated product is discharged through the other hollow trunnion. In my improvement 30 I make provision for discharging through the feed trunnion as well as the opposite trunnion, and to this end I provide an annular discharge passage around the inner feed passage in which the feed-screw or 35 spiral-thread is arranged. By making provision for a discharge at the feed end of the mill, I am able to prevent the sliming of the product to a large extent, since the material which is sufficiently fine early in the 40 action to pass through the grates at the feed end of the mill, will pass into the ribbed compartments and be carried upwardly and discharged through the annular discharge 45 opening at the feed end of the structure.

Having briefly outlined my improvement, I will proceed to describe the same in detail,

reference being made to the accompanying drawings, in which is illustrated an embodiment thereof.

In this drawing Figure 1 is a central longitudinal section taken through my improved ball or pebble mill.

Fig. 2 is a transverse section taken on the line 2—2 Fig. 1, looking toward the right.

Fig. 3 is a section taken on the line 3—3, 65 Fig. 1, the parts being shown on a larger scale.

Fig. 4 is a section taken on the line 4—4, Fig. 1.

Fig. 5 is a section taken on the line 5—5, 70 Fig. 1.

Fig. 6 is a section taken on the line 6—6, Fig. 1.

The same reference characters indicate the 75 same parts in all the views.

Let the numeral 5 designate the cylindrical shell of a ball mill, the same being composed of two substantially twin-members 6, which are provided with abutting flanges 7, the two members being secured in co-operative relation by means of bolts 8, passed through registering perforations formed in the abutting flanges which are exteriorly located. The cylindrical shell is centrally provided with two openings, which I will 80 designate by the numerals 9 and 10 respectively. Within this cylindrical casing is mounted liners 12, which cover the interior circumferential surface of the structure between the end grates 3 and 4, said grates being 85 spaced from the heads 14 and 15 by ribs 16 and 17, forming relatively narrow sector-shape compartments between the grates and the heads, the openings in the grates being of such size as to properly regulate the escape 90 of the pulverized or granular product. The grate 3 is provided with a central liner 47, which is suitably secured to the adjacent head of the structure, said liner being equipped with a conical member 18, which 95 points outwardly into the opening 9 and guides the material after it is carried upwardly and dropped by the rotary action of the mill into a hollow discharge trunnion 19. The opposite grate member 4 is equipped 100 with a centrally located liner 20, which is secured to the inner extremity of a sleeve 21 having an opening 22 which is screw-threaded for the purpose of feeding the material to be treated into the pulverizing 105 chamber of the structure, the outer extremity of the feed opening being in com-

2
munication with a feed scoop 23 which takes the material from a supply receptacle 24 and carries it upwardly and delivers it to the feed-screw of the sleeve. The said sleeve 21 is spaced from the trunnion 25 providing a discharge space 26 around the sleeve. The sleeve and the trunnion proper are spaced from each other by means of lugs 27 and 28 which are circumferentially spaced, as shown at 29, to make room for the discharge of the product at the feed end of the machine. The outer end of the trunnion 25 is equipped with an outwardly flaring member 30 which facilitates the discharge of the product into a launder 31 of any suitable character.

As shown in the drawing the grates 3 and 4 are each composed of a number of sector-shaped members 32, the grates as well as the liners being preferably formed in sections of such size that they may be replaced at small cost, when any part becomes sufficiently worn to require the substitution of a new part.

25 When the structure is in use, the trunnions are engaged by suitable boxes 33, which are supported upon pedestals 34 of any suitable construction. When in use the mill is rotated by the employment of any suitable power which may be applied through a large gear 35, a meshing pinion 36 being employed for driving purposes, the pinion being actuated by a motor of suitable character. As the structure is rotated it carries the scoop 23, which takes the material to be treated from the receptacle 24 and delivers it to the feed-screw of the sleeve 21, which carries it into the chamber of the rotary mill, where it is acted on by the balls or pebbles employed for pulverizing purposes. By virtue of the fact that provision is made for a discharge of the pulverized material at the feed extremity of the mill, the material which is sufficiently granulated or pulverized after, or shortly after it enters the mill, will pass through the grate 4 at the feed end, and will be carried upwardly in the sector-shaped compartments which are formed by the ribs 16 and 17, between the grates and the heads as heretofore explained; and this material, after it reaches a sufficient elevation in the said compartments, will be discharged into the space 26

between the trunnion and the sleeve carrying the feed-screw, and will finally escape at 55 the flaring extremity 30 of the trunnion. At the same time, the product is also being discharged through the hollow trunnion 19 at the opposite extremity of the mill from the feed-screw. Hence, it will be understood that my improved mill is equipped for a double discharge of the pulverized product, thus greatly increasing the capacity of the mill for a given tonnage of ore, and also preventing the sliming of the material treated, to a very large extent.

Attention is called to the fact that the grate 3 is secured to the adjacent head 14 of the mill by means of bolts 37. This grate is so interlocked with the central liner 47 that 70 the latter is held in place by the grate. It should be explained that the cone 18 is provided with ribs 40 which coincide as to position with the ribs 16 of the adjacent head 14 of the mill in order to form continuous passages from the sector-shape compartments between the grade and head for the discharge of the pulverized product through the hollow trunnion 19. The discharge from this trunnion enters a launder 38 from which 80 it may be conducted to the desired locality.

Having thus described my invention, what I claim is:

1. A ball or pebble mill having a central feed opening at one end and a central discharge opening at each end thereof, and segregating and delivering means for each discharge opening. 85

2. A ball or pebble mill having a central feed passage at one end and a central discharge passage at each end thereof, grates spaced inwardly from the outer heads of the mill, and means arranged between each grate and the corresponding head for elevating the pulverized material to the adjacent discharge passage. 90

3. A cylindrical ball or pebble mill having a central feed passage at one end and a central discharge passage at each end thereof, means at each end of the mill for segregating the pulverized material, and means adjacent each end for elevating such material to the corresponding discharge passage. 100

In testimony whereof I affix my signature.

DONALD H. FAIRCHILD.
